UNITED STATES PATENT OFFICE

2,599,284

OSCILLATING FAN

George J. Reisch, Stratford, Conn., assignor to
General Electric Company, a corporation of
New York

Application December 18, 1948, Serial No. 65,992

4 Claims. (Cl. 230—256)

1

My invention relates to electric fans and has for one of its principal objects to provide a new and improved oscillating fan of simple, economical construction.

Another object is to provide an oscillating mechanism completely enclosed within a fan casing comprising comparatively few component parts and operating on a principle which eliminates the usual plurality of pivotally connected arms and oscillating levers.

Another object is to arrange the component parts of a fan to obtain a proper weight distribution in order to minimize vibration and reduce friction.

A further object is to reciprocally support the operating parts of a fan so that an outer enclosing member may be easily removed without interfering with the operation of the fan, thereby permitting ready access to the motor and oscillating mechanism while in operation, making it relatively easy to adjust and repair.

A further object is to provide a single support of simple construction which serves both as a swivel stud around which a fan can oscillate and as an important part of the oscillating mechanism itself.

A still further object is to provide a new and improved means of adjustably securing the support to a base in order to quickly and easily regulate the angular elevation of a fan.

Other objects of my invention will become apparent during the course of the following description.

In general, the oscillating mechanism of my invention comprises a worm thread drive shaft, operated by a fan motor, which drives a gear train attached to an eccentrically mounted circular cam. This cam imparts a vertically reciprocating motion to a lever slidably mounted on a twisted rod. This lever, by its position contiguous to the wall of a casing which is journaled on a vertically arranged support, compels oscillation of the fan. The casing, housing the oscillating mechanism, is positioned intermediate the fan motor and the fan blades and serves to support all the operating parts of the fan. A vertically arranged support, spiralled at its upper end to accommodate the reciprocating lever, is inserted at its upper end in a swivel bearing attached to the casing at approximately the gravitational center of the fan. This support has an arcuate lower portion which is slidably fitted within a base and adjustably secured in place by a pincer mechanism.

For a more complete understanding of my in-

2

vention reference should be made to the accompanying drawings in which: Fig. 1 is a vertical sectional view of an entire fan embodying my invention; Fig. 2 is a sectional view taken along line 2—2 of Fig. 1; Fig. 3 is a sectional view taken along line 3—3 of Fig. 1; Fig. 4 is a sectional view taken along line 4—4 of Fig. 3; Fig. 5 is a sectional view taken along line 5—5 of Fig. 1; Fig. 6 is a perspective view of a suitable gear and cam assembly; and Fig. 7 is a perspective view of an oscillating lever such as may be used in my invention.

Referring to the drawings, I have shown a preferred embodiment of my invention as comprising 15 a fan having a base 1 curved to stand at a slight angle from a flat retaining member such as a table or desk. Base 1 is a wide metallic plate and may be formed to rest solidly on its opposite ends 2 and 3 without the conventional extending feet. A pair of apertures 4 and 5 aligned in the same vertical plane are formed in projecting portions 6 and 7 of base 1 in order to accommodate an arcuate lower portion 8 of a support 9, preferably in the form of a cylindrical rod which is 20 inserted through holes 4 and 5.

Another larger aperture 10 is formed in the approximate center of base 1 intermediate apertures 4 and 5 in order to accommodate a latch 11 comprising a pair of tangs 12 and 13, best seen in Fig. 2, welded or otherwise suitably attached at their outer ends 14 and 15, respectively, to the under side of base 1. These tangs 12 and 13 are composed of a slightly resilient metal and have angular flanges 16 and 17 at their adjacent ends 25 which act as pincers to securely position the support 9. The flange 16 is pressed out of the body portion of tang 12 which curves upward to form an arch 18 over the top of rod 9. When arch 18 is depressed, the angular flanges 16 and 17 move downward, releasing support 9 which may then be adjusted through apertures 4 and 5 to a different position. When the fan is at the desired tilt, the support 9 is once again secured in place by removing the downward pressure on arch 18.

45 The upper portion of supporting rod 9 is vertically arranged and has a pair of annular grooves 19 and 20 consecutively spaced from the upper end. Groove 20 accommodates a snap ring 21 which acts as a thrust shoulder supporting a 50 thrust bearing 22 comprising cup washer 23, bearing washer 24 and grease seal 25. A swivel bearing 26 having a cylindrical axial hole has a free fit over the upper portion of rod 9 and is journaled on thrust bearing 22.

55 A screw 27, best seen in Fig. 3, is inserted

through a tapped hole in swivel bearing 26 and extends into the annular groove 19 to prevent the motor assembly from being lifted away from the supporting rod 9. Screw 27 does not extend far enough to make contact with the inner wall of groove 19, and does not in any manner restrict the rotation of swivel bearing 26 around rod 9.

A casing 28, preferably rectangular, is secured to the swivel bearing 26 by any suitable means such as screws 29. This casing 28 has a thin metallic wall which can be fabricated easily by punched parts or by die-casting and serves both as a gear case and as a fan frame, indirectly supporting all the operating parts of the fan. A yoke 30 is attached by rivet 31 or otherwise suitably secured to the rear side of casing 28 and serves to support the stator and coil assembly 32 of the fan motor 32 by such means as screws 33. A circular front motor guard 34 is similarly attached to the front side of casing 28 by rivets 35 or other suitable means.

A pair of spaced bearings 36, 37 are located within centrally positioned holes 38 in the front and rear sides of casing 28. The front bearing 36 is rigidly secured in place by an annular shoulder 39 formed in the front motor guard 34 and placed against the forward portion of bearing 36; and by another annular shoulder 40 formed in a retaining strap 41 attached to casing 28 and placed against the rearward portion of bearing 36. The rear bearing 37 is similarly secured by an annular shoulder 42 formed in yoke 30 and pressed against the rearward portion of bearing 37; and by another annular shoulder 43 formed in a retaining strap 44 and pressed against the forward portion of bearing 37. A drive shaft 45, supporting the rotor assembly 46 on one end, is journaled within bearings 36, 37 and supports the fan blades 47 on its opposite end. The position of the bearings 36, 37 to one side of the rotor 46, eliminates the conventional rear end cap with bearing and permits the counterbalancing of the weight of the motor against the weight of the fan blades. It also permits a ready examination of the motor while in operation.

A plurality of washers 48 are inserted between the rotor 46 and the rear bearing 37 to reduce friction. The central washer 48 is preferably of resilient synthetic composition and acts as a cushion permitting self-alignment of adjacent parts while the motor is in operation. Another similar combination of washers 49, 49' are inserted between a snap ring 50 and the front bearing 36. The snap ring 50 is secured in an annular groove 51 in shaft 45 and acts as a thrust shoulder positioning the drive shaft 45.

An outer closing member, which may be a unitary shell 52, fits over the motor 32 and casing 28. This shell 52 has a pair of bosses 53, 54 extending from diametrically opposite sides, each boss holding a retaining pin 55 or 56. Each pin has an annular groove 57 best seen in Fig. 4 and a bifurcated conical head 58 to permit the pin to be inserted within a cylindrical aperture 59 provided in the stator laminations. The head 58 gives the retaining pins 55, 56 a small measure of resiliency which enables the pin to adhere to the laminations without the necessity of a set screw or other holding means. The usual fan guards 60 may be secured to front motor guard 34 by being hooked through suitable apertures 61 in outer shell 52 and elongated slots 61' in the motor guard 34 as illustrated in Fig. 5.

The oscillating mechanism is housed entirely

within casing 28, acting as a gear case. A worm thread 62 formed in drive shaft 45 drives a following worm gear 63 which is attached by such means as a press fit to a pinion 64, best seen in Fig. 5. Both the worm gear 63 and the pinion 64 are journaled on a bearing pin 65 which is assembled in any suitable manner to the wall of gear case 28. The pinion 64 engages the teeth of a larger spur gear 66 which is attached by such means as a press fit to a cam 67 best seen in Fig. 6. The cam 67 consists of a circular plate 68 which is eccentrically mounted on a cylindrical shaft 69, and together with the spur gear 66 is journaled on a second bearing pin 70 also attached to gear case 28. The second bearing pin 70, which serves as the pivot point for cam 67, is located directly above the upper end 71 of supporting rod 9 which extends within gear case 28. The end 71 is non-circular either elliptical or polygonal, and is twisted to form a spiraled X. In the instant embodiment I have shown this upper end as a substantially rectangular spiral. A connecting L-shaped oscillating lever 72, best seen in Fig. 7, has a circular upper portion 73 which has a slideable fit over the circular plate 68 of cam 67 and an aperture 74 in its lower leg which is suitably formed to slidably fit over the twisted end 71 of supporting rod 9. Circular upper portion 73 forms in substance an eccentric strap or collar. The width of gear case 28 is such that the upper leg of lever 73 rests against the wall 75 of gear case 28. As the lever 72 is reciprocated by the eccentric action of cam 67, a horizontal oscillatory motion is imparted by the twisted end 71 of support 9 through lever 72 to the casing 28. Since all the operating parts of the fan are supported by casing 28, the entire fan oscillates around the upper portion of supporting rod 9 by virtue of thrust bearing 22 and swivel bearing 26. A gear case cover 76 is secured in place by such means as screw 77 and serves completely to enclose the oscillating mechanism.

In the operation of my improved electric fan, the angle of elevation is adjusted by simply depressing arch 18 of tang 12, sliding support 9 within apertures 4, 5 until the desired angle is reached, and removing the pressure on arch 18. When the electric current is applied to the fan motor (connections not shown) the worm thread 62 of the motor operated drive shaft 45 rotates the worm gear 63, pinion 64, spur gear 65 and eccentrically mounted plate 68 of the cam 67. As plate 68 rotates, it imparts a circular motion to the upper end of lever 72 and a vertically reciprocating motion to the lower end of lever 72. Since the lower leg of lever 72 has an aperture 74 which fits contiguously over the spiraled end of support 9, this spiraled end 71 imparts an oscillatory force to lever 72 as it is reciprocated by cam 67. This oscillatory force is transmitted to the gear case and hence to the entire motor assembly since the gear case is pivotally journaled on the thrust bearing 22 and swivel bearing 26.

As can be seen from the foregoing detailed description, the support, which I have provided, is of simple construction and serves a multiplicity of purposes. Its arcuate lower portion serves conveniently to permit an adjustment of the angle of elevation of the fan. The vertical upper portion is formed to act as a swivel stud around which the fan can oscillate. Its upper end has a spiraled configuration which enables the reciprocating force applied to lever 72 by

cam 67 to be translated into an oscillatory motion.

The latching means which I have provided to adjustably secure the lower portion of supporting rod 9 to base 1 is both simple in construction and convenient to operate. Only slight downward pressure is necessary to release support 9 so that the angle of elevation may be adjusted. There is no necessity for the usual unscrewing and retightening of nuts and bolts.

The casing 28, although it may be no more than a rectangular box, is arranged to act as a gear case enclosing the oscillating mechanism and as a frame supporting the motor 22', the front motor guard 34, and the front and rear bearings 36, 37 for the motor operated drive shaft 45. Since this casing directly or indirectly supports all the operating parts of the fan, an outer enclosing member may be provided which is no more than a unitary shell easily removed and easily molded from a plastic compound or fabricated from metal.

It is to be understood that I do not wish to be limited to the particular embodiment of my invention that I have shown above since many modifications may be made, and I, therefore, contemplate by the appended claims to cover such modifications as fall within the true spirit and scope of my invention.

What I claim as new and desire to secure by Letters Patent of the United States is:

1. In an electric fan of the oscillating type, a casing, means for supporting said casing comprising a base, a unitary cylindrical supporting rod having a vertically arranged upper portion which provides a swivel stud on which said casing is pivotally mounted, said upper portion beyond the swivel stud having a non-circular upper end twisted to form a spiral which is positioned within said casing, and means for oscillating said casing comprising a motor operated drive shaft, a gear train driven by said drive shaft, an eccentric located above said spiralled upper end driven by said gear train, and a lever having at its upper end an eccentric strap which fits over said eccentric and at its lower end an angular portion provided with an opening in which said spiral fits, turning of said eccentric serving to reciprocate said arm on said spiral to effect oscillating movement of said casing.

2. An electric fan comprising a base, a supporting rod having a vertically arranged upper portion and a spiralled upper end, a gear case journaled on said upper portion, a motor operated shaft extending through said gear case and having a worm thread formed therein, a worm gear driven by said worm thread, a pinion attached to said worm gear, a bearing pin secured to said gear case and journaled

said worm gear and said pinion, a spur gear engaging the teeth of said pinion, a cam having an eccentrically mounted circular plate attached to said spur gear, a second bearing pin secured to said gear case directly above said spiralled upper end upon which said spur gear and said cam are journaled, and a lever for oscillating said gear case slidably mounted on said spiralled upper end and reciprocated by said circular plate.

3. In an electric fan, a vertically arranged support having a non-circular upper end twisted to form a spiral, a motor, a gear case journaled on said support and carrying said motor, a motor operated shaft extending through said gear case and having a worm thread formed thereon, and a gear train within said gear case including a worm gear driven by said worm thread, a pinion attached to said worm gear, a spur gear engaging the teeth of said pinion, a cam having an eccentrically mounted circular plate attached to said spur gear, and an L-shaped lever connected to and reciprocated by said eccentrically mounted circular plate, said lever having a hole in its lower leg formed to slidably fit on said spiralled upper end and imparting an oscillatory motion to said gear case as it is reciprocated by the rotation of said circular plate.

4. In an oscillating electric fan, a support having a vertically extending stub shaft at its upper end and a thrust bearing defining the lower end of the stub shaft, the upper end of the stub shaft being deformed to provide a spiral, a fan casing having a sleeve which fits over said stub shaft and rests on said thrust bearing, the spiral on the end of the stub shaft being positioned within the fan casing, a motor in the casing, a gearing including an eccentric driven by said motor, the eccentric being located above said spiral, and a lever having at one end a strap which fits around said eccentric and at the other end a portion provided with an opening in which said spiral fits, rotation of said eccentric serving to reciprocate said lever to effect oscillation of the fan casing.

GEORGE J. REISCH.
